UNITED STATES PATENT OFFICE

FRANCES M. MCCLURE, OF NEW YORK, N. Y., ASSIGNOR TO THE STATTON FURNITURE MANUFACTURING COMPANY, OF HAGERSTOWN, MARYLAND, A CORPORATION OF MARYLAND

DESIGN FOR A COMBINED DRESSING TABLE AND MIRROR

Application filed January 24, 1933. Serial No. 46,951. Term of patent 3½ years.

To all whom it may concern:

Be it known that I, FRANCES M. MCCLURE, a citizen of the United States, residing at New York, in the county of New York and State of New York, have invented a new, original, and ornamental Design for a Combined Dressing Table and Mirror, of which the following is a specification, reference being had to the accompanying drawing, forming part thereof,

The figure is a perspective view of a combined dressing table and mirror, showing my new design.

I claim:

The ornamental design for a combined dressing table and mirror, as shown.
